UNITED STATES PATENT OFFICE

CESARE AIRAGHI, OF GENOA, ITALY, ASSIGNOR TO ALBERT T. OTTO & SONS, OF NEW YORK, N. Y., A CORPORATION OF NEW YORK

APPARATUS FOR MOLDING CASTINGS FOR RADIATORS, BOILERS, AND THE LIKE

Application filed April 23, 1930, Serial No. 446,488, and in Italy May 6, 1929.

The present invention relates to an improved apparatus for molding simple or multiple element radiators, boilers and other similar members, and for casting these members in one unit.

The apparatus can also be utilized for the molding of different and separate groups of radiators, boilers or castings of the kind above referred to. Merely as an illustration, the invention will be described in a specific form particularly adapted to the molding and casting of radiators.

As one feature of my invention I provide a pattern plate having one side corresponding to the shape and conformation of one face of an element to be cast, and the other side corresponding to the shape and conformation of the other face of a similar element. This plate is so mounted that it may be easily and quickly moved into operative position in respect to either of two stationary pattern plates and clamped in place.

Other important features, objects and advantages will be pointed out hereinafter or will be apparent from a consideration of the specific forms illustrated and described.

In the accompanying drawings there are shown for the purpose of illustration, two forms of the present invention.

30 In these drawings:

Fig. 1 shows a front view of one form of device for forming flask moldings.

Fig. 2 shows a side view of the device of Fig. 1.

35 Fig. 3 is a section taken along line III-III of Fig. 2.

Fig. 4 shows a front view of the flasks assembled for casting operations.

40 Fig. 5 shows a side view, partly in section, of the arrangement shown in Fig. 4.

Fig. 6 shows a front view of another form of molding device.

Fig. 7 is a side view of the device shown in Fig. 6, and

45 Fig. 8 is a plan view of a portion of the device shown in Fig. 7.

In a preferred embodiment of my improved apparatus I employ two types of flasks of different heights, the shorter ones serving for the molding of the intermediate

elements of the radiator, while the others serve for the molding of the end elements of the radiators. It follows that, if two or more successive radiators are required, each radiator including a plurality of elements, 55 a larger flask should be provided in such a way that it separates the group of shorter flasks relating to one radiator from the group of the analogous flasks relating to the successive radiator. For forming a mold corresponding to an end element of a first radiator of a series, a higher flask than the others will be employed with the use of the same two pattern plates, i. e. the pattern of the movable pattern plate on the side relating to an end element and one of the two substantially stationary pattern plates. Only the mold formed on one side corresponding to the end element will be used for producing the end face of the radiator. On the contrary however, when a flask relating to the other end face of the first radiator and to the first face of the successive radiator is required, one will act in the same way by utilizing the two molds obtained in the flask. 70

These flasks will be arranged on a suitable support and will be so disposed that the first will bear against a closing plate, the second against the first flask, and so on. The last flask relating to the end of the first radiator constitutes the beginning of the second radiator or second group, and so on, up to the last flask of the last block or radiator to be cast. The latter flask will be fitted against a closing plate which is analogous to the first closing plate above referred to. 80

The two closing plates are formed with parts capable of receiving tie rods for fastening the flasks together, and parts for supporting the ends and intermediate portions of two core tubes arranged at the tops and the bottoms of the molds, each tube consisting preferably of a plurality of elements connected together in series. The different flasks are also formed with parts capable of assuring their exact relative positions even if a large number of these flasks are provided. 90

95 The foregoing method of molding and casting in a vertical direction prevents the 100

cores from deflecting and moving out of aligned position, and causes the molds to be more easily filled with melted metal.

Two devices for carrying out my invention are provided. One device is designed to prepare the molding in the end flasks of the element group and the intermediate ones, and the other designed to effect the proper assembly, connection and support of the flasks in the position suitable for casting.

The first device presents a pair of standards, each provided with a substantially stationary pattern plate. These plates are alternately subjected to the action of a compression device. This first device also presents a double faced pattern plate, movable to permit either one of its faces to be positioned opposite either one of the two substantially stationary pattern plates, and in proper position with a flask to form molds on opposite sides of said flask. The standards also present means capable of sustaining and fixing the exact position of the flasks as they are disposed on the standards, and designed to cooperate with one of the faces of the aforesaid movable plate at a time.

The flasks are open at the top for introducing the loam therein and for permitting the formation of the tap or pouring holes. The standards are provided with means capable of supporting the flasks thereon and of holding the whole quantity of loam necessary for the flasks, prior to the molding. Such means will also serve to support the quantity of loam necessary for permitting the complete and exact molding of the flask by means of the aforesaid compression device.

The second device is designed to hold in vertical position the different flasks and the cores therein in succession, as well as to fasten said flasks together so as to permit casting to be carried out.

The improvements of the present invention permit the simultaneous molding of one or more of the flasks; the simultaneous molding of both faces of the flasks; the use of flasks of different sizes on the same molding machine; proper casting even if the flasks, when coupled together and mounted for casting operation, are not exactly vertical; and the obtainment of a better separation of the slag within the feed box.

The first of the foregoing advantages has been attained in practice by providing, in addition to the press plate shown in the first form illustrated in this application, other additional plates which are so supported that they can be brought against the outer face of a flask fitted to one of the standards, and against which another flask can be applied. The second of the aforesaid advantages has been attained, whereby the press plate and the aforesaid additional plate or plates are made to press against the flask faces to be

molded, said means being mechanically controlled.

The last two advantages have been attained by providing a substantially horizontal conduit passing through from end to end of the coupled flasks, and by providing a sole feed box in communication with said conduit, and causing this conduit to communicate with the molds to be filled.

The aforesaid devices offer special advantages of rapidity, of exactitude of performance, of saving in material, and of improved workmanship.

The specific form of the device shown in Figs. 1 to 3 inclusive, includes a base 1 having two standards 2, each of which bears a pattern plate 8 and 8''. Each of the right hand and the left hand standards is provided with a piston 6 mounted in a cylinder 6' adapted to receive a liquid under pressure through an inlet 6''. Mounted on the base is a pivot 4 on which is mounted a movable arm 10 adapted to be moved into position 10 or 10' shown in Fig. 3. On the outer end of said arm is mounted a vertical pivot 10'' rotatable about its axis and carrying a rotatable plate 3. This plate 3 carries two pattern plates 8' and 8'', the plate 8' serving for the end elements of the radiator group, while the plate 8'' is similar to the pattern plates 8 and 8''', fixed to the standards. The four patterns carried by the four plates are indicated by 14, 14', 14'' and 14''', respectively. The frames 9 and 9''' for supporting the loam are yieldably supported on the standards of the machine, and two other similar frames 9' and 9'' are fixed to the rotatable plate.

The machine is provided with two types of flasks. The flask 12 of one type serves for the molding of the intermediate radiator elements, while the flask 12' of the second type is about one and two-thirds times as high as the plate of the first type, and is adapted for forming the molds for the end elements. A flask of the type 12' is mounted on the arms 13 of the machine. In bringing the cooperating parts together guiding pins (of usual type) enter the holes 5. The frame for supporting the loam, as for instance the frame 9 or 9''', is disposed against said flask 12'. The rotatable plate 3 is rotated about the pivot 4 and also about the pivot 10'', so as to present the pattern 14' or 14'' to the flask 12' according to whether it is desired to provide the end element with legs or not. The rotatable plate and the loam supporting frame 9' or 9'' are caused to bear against the flask 12'. The tie rods 11 are moved into position between spaced lugs 15 so that bosses 16 engage said lugs. The flask 12' is filled with loam from any suitable means as for instance the funnel 17. The valve (not shown) of each cylinder 6' is opened, thus causing the piston 6 to shift in the direction of the arrow 18, thereby compressing the

loam within the flask 12'. At the same time, care should be taken to see that the plane 19 of the pattern plate fits closely to the plane 20 of the flask. During the compression 5 operation, the loam supporting frames in contact with the flask 12', reacting against suitable yielding springs, shift, thus permitting the planes 19 and 20 to come together. The valve of the hydraulic cylinder 6' is then 10 closed and the exhaust valve (not shown) is opened, causing the piston to retrocede by the action of the springs 21. The plate carrying arm 10 is turned to withdraw it from the cooperating standard and the flask is removed by slipping it along the arms 13. The 15 flask is then placed on a pair of spaced supports 23 (Figs. 4 and 5), this flask being provided, for that purpose, with lugs 24. The supports 23 carry at each end a closing plate 25 which in turn carries the two tubes 26 for supporting and centering the cores 27.

The rotatable plate 3 is so movably mounted that after the aforesaid first molding takes place with the flask 12' the plate may 20 be moved in position opposite the other standard, and molding operation continued with the flask 12 already mounted thereon. The work proceeds in the same way, with the sole difference that the plate 3 must be 25 rotated 180° to present the other pattern thereon to the standard.

As to the head flasks, where the radiator element must not be provided with legs and for which it is necessary to leave the additional metal for the hubs, it is convenient to apply on the hubs of the pattern element a split ring which leaves on the molding an impression corresponding to the additional metal required.

40 The cores are formed in the usual way. In this connection, the sole variation resides in the gas outlet holes which must have the same diameter as the supporting tubes.

The other elements shown by the drawings 45 are of the usual type and therefore they do not require a particular illustration. The flasks mounted as shown in Figs. 4 and 5, are ready for the casting.

50 Referring particularly to the embodiment illustrated in Figs. 6, 7 and 8, the machine is fitted with one or more articulated arms 28' and 28'' at the end of which is mounted a press plate 29 carrying on each of its two faces a portion 30' of the pattern to be used.

55 The aforesaid fitting and the sizes of the arms are such that the pattern plate can be brought opposite to the first flask 12 supported on the standards of the machine. A second flask 30 may be supported in position on the standard on the side of the pattern plate 29 opposite the flask 12.

In the embodiment shown in Figs. 6, 7 and 8, the press plate 3 must be shiftable to effect 60 a compression substantially greater than that necessary for the embodiment shown in

Figs. 1 to 5, owing to the fact that said compression is designed to effect, by means of a loam frame 9'' carried by the press plate 3, the compression of the loam in a flask 30 and the flask 12, these flasks being separated by 70 the plate 29. These members must be moved against the pattern on the standard of the machine, which, by means of a loam frame 9''' applied thereto, provides the quantity of loam necessary for the compact filling of the 75 second flask of the group, i. e. of the flask 12.

The pivot pin 4 is mounted on a plate 31 formed with a downward extension 32 which is located between two guide members 33 capable of permitting displacements of the plate 31 and of the pin connected thereto, in the direction of the arrow 34. This is attained by means of a mechanical device provided with a threaded shaft and an end crank (not shown). The studs 36 screwed 80 to the base of the machine pass through openings 35 extending in the direction of the arrow 34. Nuts are screwed to the studs 36 to lock the plate 31 in desired position.

The articulated systems 28' and 28'' are 85 supported on the machine by means of a plate 31' which moves between the guides in the direction of the arrow 34'. The plate 31' is fixed in position by means of the studs 36' 90 screwed to the machine and passing through the slots 35' elongated in the direction of the arrow 34'.

Instead of providing a pouring hole for 95 each flask, each flask presents, according to the present invention, a hole, the various flasks coupled to each other having their 100 holes aligned to form a substantially horizontal conduit capable of being connected at the upper portion and at one or more points to the feed boxes of the metal, while said conduit is connected at its lower portion, to all the molds to be filled. Therefore, in the event that the flasks coupled to each other are not positioned on exactly horizontal supports, no practical inconvenience 105 will be experienced for the filling of the molds, whereas the separation of the slags within the feed boxes will be materially facilitated.

110 It will be possible to apply to the same machine more than one pattern plate at each end alternatively fitted with loam frame, and to adopt instead of one conduit a number of such conduits.

115 Although the present invention has been described with reference to the accompanying drawings, it is understood that the details of construction and arrangement may be widely varied.

120 Having thus described my invention, what I claim as new and desire to secure by Letters Patent is:

1. A molding apparatus including a standard, a stationary pattern plate mounted substantially vertical on said standard, a pair 125

of arms extending substantially in a horizontal position from said standard, a flask vertically supported on said arms and slidably therealong towards and away from said stationary plate, a pattern plate movably supported with respect to said stationary pattern plate and movable towards and away from said flask, pressure means for forcing said flask and said plate on both sides thereof into close molding relationship, and spring means for separating said flask from its adjacent pattern plates upon the release of said pressure.

2. A molding apparatus including a pattern plate substantially stationary, a flask, means for supporting said flask on said machine into molding relationship with said stationary plate, said last mentioned means permitting slidable movement of said flask towards and away from said stationary pattern, a pattern plate movably supported with respect to said stationary pattern plate and adapted to be moved into molding relationship with the outer side of said flask, pressure means for pressing said movable plate, flask and stationary pattern plate into close relationship, and means for gradually separating said plates and said flask as the pressure effected by said pressure means is released.

3. A molding apparatus including a pair of stationary interspaced pattern plates, means for supporting a flask in juxtaposed molding relationship with either of said pattern plates, an arm pivoted at a point between the two pattern plates, a plate pivotally mounted to said arm so as to be rotatable about its own axis and movable about the pivot axis of said arm, said latter plate having patterns on opposite sides thereof, and said arm being of such length that either of the patterns on said movable plate may be moved into molding relationship with the flask on the side thereof opposite either one of said stationary plates.

4. A molding apparatus including two substantially stationary pattern plates, means on said machine for supporting a flask in juxtaposed relationship with respect to said pattern plates, and a pattern plate movably supported with respect to said apparatus and adapted to be moved in opposite molding relationship with respect to either one of said first mentioned pattern plates.

5. A molding apparatus including a pair of pattern plates substantially stationary, means for supporting a flask in juxtaposed molding relationship with either of said pattern plates, an arm pivoted at a point between the two pattern plates, the pivot point of said arm between the two pattern plates being movable in a direction substantially at right angles to the two plates, a plate pivotally mounted at one end of said arm so as to be rotatable about its own axis and movable

about the rotative axis of said arm, said plate having a pattern on one side thereof, and said arm being of such length that the pattern on said movable plate may be moved into molding relationship with either one of said stationary pattern plates. 70

6. A molding apparatus including a standard, a stationary pattern mounted substantially vertically on said standard, a pair of arms extending substantially in a horizontal direction from said standards in front of said pattern, a flask having projecting members extending outwardly from the vertical sides of the flask intermediate the ends thereof, said flask being supported on said arms in substantially vertical position, and slidably along said arms towards and away from said stationary pattern, a pattern disposed between said arms on the side of said flask opposite the first mentioned pattern, and movable towards and away from said flask, and means for forcing said flask and said patterns on both sides of said flask into close molding relationship. 75

7. A molding apparatus including a standard, a stationary pattern mounted substantially vertically on said standard, a pair of arms extending substantially in a horizontal direction from said standards in front of said pattern, a flask having projecting members extending outwardly from the vertical sides of the flask intermediate the ends thereof and supported on said arms in substantially vertical position, said flask being slidably along said arms towards and away from said pattern into molding relationship therewith, and means for forcing said flask and said pattern into close molding relationship. 80

8. A molding apparatus including means for supporting a pair of flasks vertically in interspaced relationship, an arm pivoted at a point between the mountable position of said flasks, and a vertical pattern plate pivotally mounted on said arm in a position whereby said pattern plate may be moved into molding relationship with either one of said flasks. 85

9. A molding apparatus including a pair of stationary interspaced pattern plates mounted substantially vertically, means for mounting flasks in molding relationship with said stationary plates, an arm pivoted at a point between said pattern plates, and a pattern plate pivotally mounted on said arm, whereby said last mentioned plate may be moved into molding relationship with either one of said flasks on the side of said flasks opposite said stationary plates. 115

10. A molding apparatus including means for mounting a pair of flasks vertically in interspaced relationship, an arm pivoted at a point between the mountable position of the two flasks, a plate pivotally mounted on said arm so as to be rotatable about its own 120

axis, and movable about the pivot axis of said arm, said plate having patterns mounted on both sides thereof, whereby either one of said patterns may be moved into molding relationship with either one of said flasks.

11. A molding apparatus including two pairs of interspaced arms extending substantially in a horizontal direction, each of said pairs of arms being adapted to support a flask vertically, a member pivoted between the two pairs of arms and pivotally carrying a pattern plate thereon, said plate being movable between the arms of either one of said pair, and into molding relationship with the flasks mounted on said arms.

12. A molding apparatus including a frame structure having a vertical surface, means for supporting a flask, and a pattern vertically in molding relationship with each other and against said vertical surface, a fluid pressure piston mounted on said frame structure, and adapted to move away from said surface when subjected to fluid pressure, a pair of arms connected to said piston for movement therewith and extending on opposite sides of the molding position of said flask and said pattern, and means on said arms for holding said flask and said pattern against said surface in molding position under the pressure action of said piston.

13. A molding apparatus including a frame structure having a vertical surface, means for supporting a flask and a pattern vertically in molding relationship with each other and against said vertical surface, a fluid pressure piston mounted on said frame structure and adapted to move away from said surface when subjected to fluid pressure, a pair of arms connected to said piston for movement therewith, and extending on opposite sides of the molding position of said flask and said pattern, said arms being pivoted about vertical axes near sections where said arms are connected to the piston, whereby said arms may be swung towards or away from the vertical sides of said flask and said pattern, and means on said arms for holding said flask and said pattern against said surface in molding position under the fluid action of said piston.

14. A molding apparatus including a frame structure having mounted thereon a vertically extending pattern facing the front of said structure, means for vertically supporting a flask in molding relationship with said pattern, and adapted to move away from said pattern when subjected to fluid pressure, a pair of arms connected to said piston for movement therewith, and mounted on opposite sides of said flask and pattern, for holding said flask and pattern in molding relationship under the influence of said fluid pressure on said piston.

15. An apparatus for forming molds for the sections of a radiator, including a stand-

ard, a stationary pattern for the intermediate sections of the radiator, mounted substantially vertically on said stand, means for mounting a flask vertically in molding relationship with respect to said pattern, and a plate having a pattern on one side thereof for the intermediate sections of said radiator, and a pattern on the other side for the end sections of said radiator, said plate being movably mounted in respect to said stand, so that either pattern thereon may be moved into molding relationship with said flask on the opposite side from said stationary plate.

Signed at Genoa, Italy, this second day of April, 1930.
